Inventor:

Francis H. Richards.

UNITED STATES PATENT OFFICE.

FRANCIS H. RICHARDS, OF SPRINGFIELD, MASS., ASSIGNOR TO THE AMERICAN BUTTON FASTENER COMPANY, OF NEW BRITAIN, CONN.

PUNCH.

SPECIFICATION forming part of Letters Patent No. 353,817, dated December 7, 1886.

Application filed October 30, 1885. Serial No. 181,384. (No model.)

To all whom it may concern:

Be it known that I, FRANCIS H. RICHARDS, a citizen of the United States, residing at Springfield, in the county of Hampden, State 5 of Massachusetts, have invented certain new and useful Improvements in Pliers, of which the following is a specification.

This invention relates to that class of pliers which, when provided with suitable dies or 10 tools, are used for belt-punches and eyelet and button-fastener setting instruments.

The principal object of the invention is to furnish an implement of the aforesaid class in which the jaws shall have as they approach 15 each other a decreasing movement relative to the movement of the handles, thereby securing a greater power toward the end than at the beginning of their closing movement.

To this end the invention consists in the combination hereinafter described and claimed.

In the drawings accompanying and forming a part of this specification, Figure 1 is a side elevation of an implement embodying my invention, the jaws of the implement being in 25 their open position. Fig. 2 is a similar view showing the relative positions of the parts when the jaws are partly closed. Fig. 3 is a similar view showing those positions when the jaws are closed. Fig. 4 is a top view of the 30 implement. Fig. 5 is a cross sectional view in line *a a*, Fig. 3.

Similar characters designate like parts in all the figures.

My improved pliers comprise the member 35 A, composed of a fixed jaw, 2, and handle 6, together forming one side of the implement, the member B, which is a movable jaw having pin 7, and the member C, which is a lever having a pin, 5, and having a handle, 8, corresponding to handle 6. Members B and C are each pivoted on member A at 4 and 3, respectively. Connecting pins 5 and 7 there is a plain link, 9, which forms with part of member C a sort of inverted toggle-joint for 45 operating member B. Said link and pins are so arranged as to move part B more rapidly relative to the movement of handle 8 at the beginning than toward the end of its closing stroke. This action will be apparent upon 50 comparing with each other the first three figures of drawings. In Fig. 1 the handles and jaws are both widest open. In Fig. 2 the handles have been brought toward each other about one-third of their stroke, and this,

owing to the construction of the toggle, has 55 about two-thirds closed the jaws. On now continuing the closing of the handles the jaws have a retarded motion, closing more slowly, but with correspondingly greater power, so that both the jaws and the handles 60 reach their closed position together, as in Fig. 3, wherein the three centers 3, 5, and 7 stand about in a straight line. On opening the handles, which may be done by a spring (not shown) in the ordinary way, the relative 65 movements of the jaws and handles will of course be reversed.

It should be understood the instrument may be specially proportioned and arranged in various ways, to adapt it for the different purposes for which it is to be used. In the present instance I have shown it as used for a belt-punch, 10 being the punch, and 12 the copper plate on which the punch acts.

It is not the sole object of my invention to 75 furnish pliers in which the jaws shall have the retarded closing movement above described. It also aims to furnish a tool of the class specified in which the jaws shall move through a given distance with less angular movement 80 than common to ordinary implements of the same size. This object I accomplish by pivoting together the members A and B farther back than usual toward the handles and providing means for operating them from a point 85 forward (toward the left hand in Fig. 1) of said pivot. That is to say: The handle C being pivoted to member A at 3, forward of pivot 4, the member B may be made much longer than it otherwise properly could be in 90 an instrument of a given size. This secures a minimum of angular movement of member B as compared with the vertical stroke of its front (left-hand) end.

Having thus described my invention, I 95 claim—

The improved plier or like instrument herein described, it comprising the member A, the member B, pivoted to member A at 4, rearward of pivot 3, the lever C, pivoted to member A at 3, forward of pivot 4, and a link connecting lever C with member B and operating as a toggle to impart a retarded movement to said member B, all substantially as described.
